[57] CLAIM

The ornamental design for an electric heater element
for use in a radiant heater for a glass ceramic hob, as
shown and described.

DESCRIPTION

FIG. 1 is a top plan view of an electric heater element
for use in a radiant heater for a glass ceramic hob, showing
our new design, the bottom being a mirror image of
that shown;

FIG. 2 is a front elevation view thereof, the rear being
a mirror image of that shown;

FIG. 3 is a right side elevation view thereof; and

FIG. 4 is a left side elevation view thereof.
The broken line showing of a radiant heater for a glass
ceramic hob in FIG. 1 is for illustrative purposes only
and forms no part of the claimed design.
